UNITED STATES PATENT OFFICE.

WILLIAM ELI ROACH, OF SAN ANTONIO, TEXAS.

ACCOUNT-INDEX.

1,077,752.

Specification of Letters Patent.

Patented Nov. 4, 1913.

Application filed December 4, 1912. Serial No. 734,877.

To all whom it may concern:

Be it known that I, WILLIAM ELI ROACH, a citizen of the United States, and a resident of San Antonio, in the county of Bexar and State of Texas, have made certain new and useful Improvements in Account-Indexes, of which the following is a specification.

My present invention relates to indexes, more particularly to card indexes, my object being to provide such an arrangement that cards may be held in a series in which a portion of each card is visible, these cards being reversible and each having upon one face account entry rulings and having upon its opposite face a symbol which when turned to view will serve to call attention to the particular card.

In accordance with my invention the cards and their supports are so formed that the former may be reversed. Thus, the cards on which the accounts are due may be turned so as to expose the indicating symbols above mentioned and thus permit of the account due cards being readily and quickly distinguished from the remaining cards.

In the accompanying drawing, which illustrates a construction and arrangement forming the basis of my present invention, Figure 1 is a front elevation of a card supporting member in connection with a plurality of account cards. Fig. 2 is a longitudinal section taken substantially on the line 2—2 of Fig. 1. Fig. 3 is an elevation of the account card, looking at its obverse side. Fig. 4 is a similar view looking at its obverse side. Fig. 5 is an elevation of a portion of a support constituting a modified form of my invention, and Fig. 6 is a detail transverse section, taken substantially on the line 6—6 of Fig. 5.

Referring now to these figures, particularly to Figs. 1 and 2, the support A consists of a relatively thin sheet which may be formed of any suitable material so as to be adapted for disposal within an upright position in a box or suitable container or to adapt it to constitute one of the leaves of a loose leaf book. As also particularly indicated in these figures, the support A includes a suitable series of spaced parallel folding arms *a*, upon each of which one of the cards B, B', B², B³, B⁴, B⁵ and B⁶ is disposed. This support may, however, be of various other forms, for instance the form as indicated at C in Figs. 5 and 6, the

body of which comprises a strip upon one face of which is secured a supplemental strip *c* of substantially reduced width, the several arms *c'* being formed at one end with integral lips *c*² struck out therefrom so as to oppose the said ends of the arms and form a clasp by which the body strip of the support C may be clasped. Thus, where the last described construction is used in connection with fast growing account lists requiring a number of changes, for instance, each day, a new name or card with its arm can be inserted in proper alphabetical position by simply sliding the cards already in position up or down on the strip C, thus obviating the necessity of removing the cards and repositioning them as would be necessary with the construction described in connection with Fig. 1.

Each of the cards has one longitudinal edge portion *b* bent back and secured to the rear face of the card so as to form a guide opening or channel in which the holding arms *a* or *c'* may be received, the card being further provided upon its obverse side with account rulings and with name and residence spaces upon both its obverse side and upon the bent edge portion *b* of its reverse side as will be seen by comparison with Figs. 4 and 5. Each card is also provided upon its bent back edge portion *b* with a suitable symbol, here shown as a transverse stripe *b'* of a red color so as to quickly catch the eye.

In practice those cards on which an account is due, are placed in their proper positions upon the support, with their reverse sides foremost, the indicating symbols *b'* clearly showing that something is due to be paid and thus obviating the necessity of running over the entire number of cards when it is desired to make a total of the unpaid accounts. As soon as the account is settled the card is removed from its holding arm, an entry of the payment is made in the proper place, after which it is reversed and replaced on the arm its symbol is hidden.

An account index constructed substantially as I have shown and described will be the means of saving a great amount of time where a great number of accounts are kept such as for instance, lodges, secret societies and in fact many businesses.

I claim:

1. An account index comprising the combination of a plurality of superposed parallel holding arms, and a plurality of cards

having guides for reversible engagement with the said holding arms.

2. An account index card having one edge portion bent back and secured upon its reverse side whereby to form a channel along the said card edge, said card having name spaces both upon its obverse side and upon the said turned back edge portion on its reverse side, for the purpose described.

10 3. An account index comprising the combination of a holder, a plurality of laterally outstanding arms having a sliding connection with the holder and adapted to main-

tain themselves in selected position thereon, and a plurality, of cards having detachable 15 and reversible engagement with the said arms.

4. The combination of a card supporting member having a plurality of superposed outstanding arms, and a plurality of cards 20 having guides detachably and reversibly engaged with the said arms.

WILLIAM ELI ROACH.
